(57) **CLAIM**

The ornamental design for a barbell handle for a drink container as shown and described.

DESCRIPTION

FIG. 1 is a side perspective view of a barbell handle for a drink container showing my new design;

FIG. 2 is front view thereof;

FIG. 3 is a back view thereof;

FIG. 4 is a right view thereof;

FIG. 5 is a left view thereof;

FIG. 6 is a bottom view thereof;

FIG. 7 is a top view thereof; and,

FIG. 8 is another side perspective view.

The broken lines showing a drink container illustrate environment and form no part of the claimed design.

1 Claim, 6 Drawing Sheets
